NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING-MACHINE TRUCK.

1,392,836.

Specification of Letters Patent.

Patented Oct. 4, 1921.

Application filed November 21, 1916, Serial No. 132,683. Renewed April 3, 1920. Serial No. 371,148.

To all whom it may concern:

Be it known that I, NILS D. LEVIN, a citizen of the United States, residing at Columbus, in the county of Franklin and the State 5 of Ohio, have invented certain new and useful Improvements in Mining-Machine Trucks, of which the following is a specification, reference being had therein to the accompanying drawing.

10 The present invention relates to certain new and useful improvements in mining machine trucks, and especially to improvements in wheeled trucks, each of which is adapted to travel along the tracks of a mine to transport a mining machine from one working 15 place to another and which is adapted to the convenient unloading of the mining machine preparatory to its operation and to the reloading of the said machine after the 20 completion of said operation.

In the mining of coal in accordance with the room and pillar system machines are commonly used which are adapted to cut horizontal kerfs at the base of the coal body 25 across the end of the room. As the working faces are commonly short, seldom exceeding twenty-five or thirty feet, such machines are capable of cutting a number of working 30 places in a single shift, and it is necessary, for economical operation, to provide means to expeditiously transport the machine from a completed room to the next one to be cut.

It is the especial object of this invention to provide a truck of the class described, 35 especially adapted to use in a very low vein of coal, wherein the forward end of the truck may be lowered to discharge or to receive a mining machine without a corresponding elevation of the devices mounted upon the 40 rear end of the truck.

Another object is to provide improved retarding devices by which movement of the truck along the tracks of the mine may be checked.

45 These and other objects will appear in the following specification reference being had to the accompanying drawings of which—

Figure 1 is an elevation of the preferred embodiment of my invention.

50 Fig. 2 is a plan view of the machine shown in Fig. 1.

Fig. 3 is a side elevation of the truck in position to receive or discharge a mining machine.

Fig. 4 is a section along the line 4—4 of 55 Fig. 2.

Fig. 5 is a section along the line 5—5 of Fig. 2.

Like numerals refer to similar parts in the several figures.

My improved truck, as illustrated in the drawings, consists essentially of a wheel supported frame which is divided transversely near the middle of its length and the two parts connected by a suitable hinge. 65 The forward section consists of the longitudinal angle bars 1 and the cross members 2, 3, and 4 which are securely riveted together. Near their forward ends the longitudinal angles 1 are bent outwardly to facilitate the entrance of the mining machine between the upstanding flanges 5 by which it is guided to and retained in place upon the truck. To the lower sides of the angle bars 1 are secured the journal boxes 6 and to 75 these are attached the forwardly extending truss bars 7 which are attached at their forward ends to the angle bars 1 to stiffen the frame. In these journal boxes 6 is mounted the front axle 8 the wheels 9 of which 80 are adapted to travel along the rails 10 of the mine track.

The rear section of the frame consists of the longitudinal angle bars 11 joined by the cross members 12, 13 and 14. To the cross 85 members 3 of the front section is secured the hinge castings 15 having apertures registering with similar apertures in the hinge lock 16 fixed to the cross member 11 of the rear section and through these apertures 90 extends the hollow shaft 17 by which the two parts of the frame are joined together. To the under side of the longitudinal angle bars 11 are attached the journal boxes 18 in which is mounted two rear axles 19 to which 95 are attached the wheels 20 adapted to travel along the rails 10. Truss bars 21 are attached at their rearward ends to the angle bars 11 and are secured to the under sides of the journal boxes 18 and the hinge blocks 100 16 to stiffen the frame.

The forward section of the truck constitutes a skid frame along which the mining machine may be conveniently moved and upon which it rides while being transported 105 from place to place. This skid frame extends rearwardly of the hinge between the upstanding flanges 22 of the angle bars 11

which engage the flanges 5 to impart lateral stiffness to the truck and relieve the hinge of strain due to curves and irregularities of the track. A latch 23 attached to the cross member 13 is adapted to engage the flange 24 of the cross member 4 to hold the two sections of the truck in proper relation for traveling. A bracket 25 attached to the cross member 4 is arranged to form a convenient coupling for the handling rope 25^a of the mining machine to draw the machine onto the truck.

Attached to the axle 8 is a sprocket wheel 26 which is adapted to be connected through a suitable endless chain 27 with a sprocket wheel 28 upon the mining machine, to transmit power from the motor of the mining machine to the driving wheel of the truck to propel it along the mine tracks. As the arrangement of parts of the mining machine are set forth in my copending application Serial No. 132,681, filed November 21, 1916, a description of them at this time is not thought to be required.

The axles 8 and 19 are coupled together through the sprocket wheel 29 and 30 and the endless chain 31 in the manner common to self-propelling trucks. Attached to the axle 19 is a brake drum 32 encircled by a brake band 33. The brake band 33 is attached at one end to the brake shoe 34 which is pivotally attached to a brake lever 35 by a pin 36. The ends of the pin 36 project on either side of the brake shoe 34 and extend into the slots 37 of the lugs 38 projecting downwardly from the truck member 12 to support the brake mechanism. The other end of the brake band 33 is adjustably attached to the lower end of the brake lever 35. Connected with the upper end of the brake lever 35 is a rearwardly extending pull rod 39 which is connected with the hand lever 40 pivotally mounted upon the truck member 13. When the hand lever 40 is rotated rearwardly the brake shoe 34 is drawn against the brake drum 32 and the lower end of the brake lever 35 is rotated about the pin 36 to tighten the brake band 33 to resist the rotation of the axle 19 and as the axles 8 and 19 are connected together through the chain 31 to also resist the rotation of the axle 8 to check the movement of the truck along the track. A notched arc 41 is provided to engage the hand lever 40 and maintain tension upon the brake.

As the floor of the mine follows the dip of the coal vein and the tracks are commonly laid directly upon the floor, the grades of mine tracks are often so steep that the retardation of the wheels does not afford sufficient control of the movements of the truck. To meet such conditions I have provided an auxiliary brake comprising shoes 42 adapted to engage the track rail. The shoes 42 are attached to stems 43 which are

vertically movable in apertures of the cross bars 13 and 44 of the truck frame. Formed in the stems 43 are recesses 45 which engage the forked rocker arms 46 attached to either end of the shaft 47 which is rotatably supported in the hollow hinge shaft 17. An auxiliary bearing 48 affords additional support for the shaft 47. Attached to the shaft 47 is an upstanding arm 49 to which is connected the pull rod 50. The rod 50 is also connected to a rocker arm 51 attached to a short horizontal shaft 52 journaled in apertures of the auxiliary frame 53 attached to the truck frame near its rear end. Journaled in the auxiliary frame 53 is a vertical shaft 54 to the top of which is attached a hand wheel 55 for its manipulation. The shaft 54 is screw threaded and is provided with a nut 56 in engagement with the rocker arm 57 of the horizontal shaft 52. When the hand wheel 55 is rotated in one direction the nut 56 travels upwardly and rotates the shaft 52 to pull the rod 50 thereby rotating the shaft 47 to force the brake shoes 42 into contact with the track rails 10 and retard the movement of the truck along said rails. A rotation of the wheel 55 in the reverse direction moves the brake shoe away from the track and allows free movement of the truck.

Mounted upon the rear end of the truck is a cable reel 58 upon which is windable a conductor cable 59 the free end of which is adapted to be connected to any convenient stationary source of electrical supply, such as the trolley wires suspended above the tracks in the entries of the mine. Through this cable is supplied the electric current to actuate the motor of the mining machine, both for propelling the truck and for operating the mining machine. The cable reel 58 is provided with trunnions which are supported in journal bearings 60 carried by a U shaped frame 61 the ends of which bear on suitable supports on the truck frame. Electrical connections are made through the bearings 60 between the cable 59 and a similar cable 62 which extends to the mining machine and is adapted to be connected therewith whether the mining machine is positioned upon the truck or upon the floor of the mine. Attached to the cable reel 58 is a rope sheave 63 about which passes an endless rope belt 64 which also engages a sheave 65 attached to a horizontal shaft 66 journaled in bearings 67 of the truck frame. The shaft 66 is connected with the axles 19 through the sprocket wheels 68 and 69 and the endless chain 70. By this arrangement of parts movement of the truck along the rails 10 rotates the reel 58 to wind or to unwind the cable 59 according to whether the truck is approaching or moving away from the point of attachment of the cable to the trolley wire. The

support of the frame 61 upon the truck is so positioned with relation to the center of gravity of the reel 58 that a part of the weight of the reel will be carried by the rope 5 belt 64 to produce the proper belt tension to wind the cable 59 or to allow a slippage of the belt 64 when the strain on the cable is in excess of a predetermined amount. A casting 71 having chain engaging flanges 72 is 10 attached to the truck frame to deflect the chain 70 to afford clear space for the handling of the mining machine.

When the truck, with the mining machine upon it has arrived at the place where the 15 machine is to be unloaded, the handling rope of the mining machine is drawn out and secured to a suitable anchor in advance of the machine. The latch 23 is then disengaged from the flange 24 and the machine 20 drawn forward. As the center of gravity of the mining machine passes the axle 8 the ends of the truck drop to contact with the floor of the mine and the mining machine may slide smoothly off the truck. When 25 reloading, the handling rope of the mining machine is attached to the bracket 25 and the machine is drawn onto the skid angle bars 1. As the center of gravity of the mining machine passes rearward of the axle 8 the mid- 30 dle part of the truck frame will be depressed to elevate the ends and the latch 23 reengaged with the flange 24 to maintain the traveling relation of the truck sections. Before the machine is moved forward for un- 35 loading the chain 27 is removed from the sprocket wheel 28 to allow the mining machine to move freely from the truck. When reloading, as the machine moves back along the angle bars 1, this chain 27 is replaced 40 upon the sprocket wheel 28 so that as soon as the machine is in place the truck is ready to travel.

When trucks of this sort are used for transporting mining machines they must 45 sustain a heavy weight, the machines weighing four thousand pounds or more. The forwardly projecting part (the cutting apparatus) of one of the mining machines is from seven or eight to ten feet long, but relatively light, while the parts at the rear end of the mechanism are exceedingly heavy, these comprising the heavy electric motor or engine, the shafting and gear wheels for driving the cutting apparatus, and for effecting the movement of the machine bodily 55 over the ground, the feeding devices comprising heavy masses of cable on reels and heavy driving mechanism.

When the tilting of the body frame or 60 skid frame 1 is depended on to cause the forward and downward sliding of the mining machine to the floor considerable labor or exertion of power is required to elevate the rear part of the skid body. The higher this 65 end is elevated the more readily will the

machine move forward. Heretofore when tilting skid frames or body frames were used for supporting these machines, the frames were hinged at an axis considerably above and forward of the front wheel axis. The 70 result was to throw the rear end of the body frame to a high plane when it was discharging the machine. But in low mines there is not sufficient room to permit the swinging of the rear end of this frame to a high 75 plane in order to get a sharp downward inclination toward the front.

I have provided a construction of parts and have so related them that the lifting of the rear end of the frame is facilitated by 80 the actions of various parts of the apparatus itself and the tilting is effected around a line in a low plane.

Moreover, I provide means for applying power to the rear end of the body frame to 85 assist in lifting it at the time when the heavy part of the mining machine is resting upon that end. The rear section of the frame is extended a considerable distance behind the rear axle, and upon this rearwardly extending part of the frame is supported the reel with a heavy mass of copper and also the shafting and gearing by which power is transmitted to the reel, and also the parts by which the movements of the apparatus 95 as an entirety along the track rails is controlled.

Consequently when the lock between the two frame sections is opened the rear frame section can be utilized for leverage, as power 100 can be transmitted from its longer rear arm around the rear wheel axle and through its forward shorter arm to the rear part of the front or skid frame section and cause the latter, and the machine thereon, to immediately commence to tilt. Power for this purpose is derived from the gravity of the heavy parts carried by the rearward extending arm of the rear frame section.

As a result of these matters not only is 110 there compensation for the elongating of the rear part of the body frame or skid frame to transverse lines which are considerably behind that of the front axle, but there is a positive application of power 115 to assist in lifting the rear end of the front frame section and as the said section tilts around a low horizontal axis, the parts of the apparatus are quickly, and practically automatically, brought to the positions 120 where the front frame section allows the machine to easily slide forward to the ground.

I am aware that four-wheeled trucks have 125 been heretofore proposed, each to have two frame sections hinged together, of which sections each was to be mounted so as to tilt on a transverse axis. But in the constructions so proposed, each of the frame sections was substantially a duplicate of the other. The 130

hinging devices were to unite the adjacent parts of the frame sections on an axial line at the rear extremity of the front section and at the front extremity of the rear section, the two sections being similar to each other, and similarly mounted; and the joining hinge being at the extremities of the adjacent ends, neither was adapted to exert any leverage on the other and, particularly, 10 neither was adapted to cause a relatively longer movement of the end of its companion section while it moved through a relatively short path at its end.

In my mechanism a short vertical movement of the rear arm of the forward frame section results in a much longer movement of the rear extremity of the front frame section. The union hinge axis is in a plane, transverse to the front section, which is intermediate of the ends of the rear arm of that section. By preference this hinge axis is located considerably nearer the axis of support (the wheel axis) of the front frame section than it is to the rear end of that 25 section. Consequently a slight movement vertically of the front end of the rear frame section causes a much longer movement of the rear end of the front section.

What I claim is—

30 1. In a truck of the class described, the combination of two frames each mounted for rotation about a wheel supported axle, a hinge connecting the frames, means to rotate the axle to propel the truck, and means independent of the axles to engage the track rails to retard the truck.

40 2. In a truck of the class described, the combination of a skid frame adapted to receive and support a mining machine, a second frame hinged to the skid frame, each frame supported upon and rotatable about a wheel supported axle positioned between said hinge and the end of its respective frame, and means to prevent movement of 45 the frames relative to each other.

50 3. In a truck of the class described, the combination of two frames each mounted for rotation about a wheel supported axle, a hinge connecting the frames, means to prevent movement of the frames relative to each other, means to rotate the axles to propel the truck and means independent of the axles to engage the track rails to retard the movement of the truck.

55 4. In a truck of the class described, the combination of two frames each mounted for rotation about a wheel supported axle, a hinge connecting the frames, means to prevent movement of the frames relative to 60 each other, means to rotatively connect the axles, means to rotate the axles to propel the truck and means to engage the track rails to retard movement of the truck.

65 5. In a truck mechanism of the class described, the combination of a front load

carrying frame section mounted to tilt vertically around an axis in a transverse plane intermediate of the ends of the frame section, and a second frame section mounted to tilt vertically around an axis in a transverse plane intermediate of the ends of said section, and which is hinged to the first frame section at a transverse axis between its supporting axis and its rear end, the forward end of the second section being adapted to transmit power to the first section to elevate its rear end. 70 75

6. In a truck mechanism of the class described, the combination of the front load-carrying frame section, mounted on a wheel support at an axis in a transverse plane intermediate of the ends of said section and arranged to have its rear end lie under and engage with the rear end of the load when the latter is in normal position on the truck, 80 and a second frame section mounted on a wheel support having its axis in a transverse plane relatively near the front end of said rear section, and the rear part of said rear frame extending relatively a long distance behind its axis, the front short arm of the rear section being hinged to the front section at an axis close to the axis of mounting of the front section. 85 90

7. In a truck of the class described, the combination of a front frame section, and a rear frame section, each mounted independently of the other on wheels at an axis in a transverse plane intermediate of its ends, the forward end of the rear section being 100 hinged to the rear part of the front section at a transverse line in front of the rear end of the front section, and the rear end of the front section extending from the hinge backward over the rear section whereby the rear section can be caused to raise the rear end of the front section a relatively long distance above the plane of the hinge. 105

8. In a truck of the class described, the combination of a wheel supported axle, a load-carrying frame section tiltably connected to said axle at an axis in a transverse plane intermediate of the ends of said section, a second wheel supported axle, and a second truck-frame section tiltably connected to the second axle at an axis in a transverse plane intermediate of the ends of said second section, one end of said second section being hinged to the first section at a transverse plane remote from the rear end of the latter, whereby a relatively short movement of the second section causes a relatively long movement of the rear extremity of the first section. 110 115 120

9. In a truck of the class described, the combination of a wheel supported axle, a load-carrying frame section connected to said axle and tiltably around an axis in a transverse plane intermediate of the ends of said section, a second wheel mounted axle, 130

and a second truck-frame section mounted on the second axle and hinged to the first frame section at a transverse line remote from the rear end of said first section, said 5 second frame section extending to the rear of the said second axle a relatively long distance whereby it is adapted to transmit power to the first frame section and elevate the rear extremity of the latter to a horizontal plane above the plane of the hinge axis.

10. In a truck of the class described, the combination of a front load-carrying frame section mounted on wheels to tilt vertically around their axis, which axis is in a transverse plane intermediate of the ends of said front section, and the second truck-frame section mounted on wheels to vibrate around their axis, which axis is in a transverse plane 20 intermediate of the ends of said second section and the latter being hinged to the first section at a transverse line, which is intermediate of the ends of the first section, and the second frame section being adapted to 25 transmit power to the rear extremity of the front section and lift it to a horizontal plane higher than the plane of the hinge axis.

11. In a truck mechanism of the class described, having two wheel mounted axles, two vertically tilttable frame sections hinged together, one being a load-carrying frame which when in normal position extends longitudinally backward from the hinge axis over the other frame section and over the rear axle, each frame section being pivoted 30 on its own axle, and the front end of the forward section being normally free to tilt downward when the front end of the rear section tilts upward.

12. In a truck mechanism of the class described, having two wheel mounted axles, two vertically tilting frame sections hinged together and each adapted to swing about a wheel axis, one of said sections extending from the hinge axis backward to overlie the 45 forward part of the other section and over the rear axle.

In testimony whereof I affix my signature, in the presence of two witnesses.
